UNITED STATES PATENT OFFICE.

KARMELL BROOKS, OF NEW YORK, N. Y.

FOLDING BED.

SPECIFICATION forming part of Letters Patent No. 367,695, dated August 2, 1887.

Application filed July 30, 1886. Renewed June 18, 1887. Serial No. 241,798. (No model.)

To all whom it may concern:

Be it known that I, KARMELL BROOKS, of the city, county, and State of New York, have invented a new and useful Improvement in 5 Folding Beds, of which the following is a full, clear, and exact description.

My invention relates to certain improvements in folding beds, and has for its object to provide a take-up for the woven-wire mattress ordinarily used in such form of beds, whereby the tension brought to bear upon said mattress in taking up the slack will be equally distributed over the entire surface thereof, and whereby the mattress may be loosened and 15 tightened at pleasure, with the least amount of exertion, through the medium of a simple, effective, and durable construction, and also to effect an improvement in the means for supporting the sections of a folding bed.

It consists in the construction and combination of parts, as will be hereinafter fully described, and set forth in the claims.

Reference is to be had to the accompanying drawings, forming a part of this specification, 25 in which similar letters of reference indicate corresponding parts in all the figures.

Figure 1 is a longitudinal vertical section through the bed when in position for use. Fig. 2 is a transverse vertical section thereof, parts 30 broken away. Fig. 3 is a longitudinal vertical section of the bed when folded up. Fig. 4 is a front elevation of the bed-bottom, showing the foot-section folded over upon the head-section thereof. Fig. 5 is a transverse vertical section through the foot-section, looking 35 toward the foot-board; and Fig. 6 is a detail view of the pivotal connection of one set of legs.

The frame of my folding bed consists of the 40 head-board 1, provided with curved projecting sides 2, a hinged top cover, 3, adapted to fold parallel with the head-board when not in use as a cover, between the upper narrow portion of the projecting sides 2 and a lower 45 hinged angular casing, 4, adapted to conceal a torsion-spring, whereby the bed is balanced. Said casing 4 is notched at the junction of its lower edge and ends to engage the top edge of the side boards, 6, which are pivoted at 7 to 50 the extended portion of the projecting sides 2

and adapted to be swung upon their pivots when folded over, as hereinafter described, to a vertical position within said sides. A suitable base carrying casters is provided for the head-board, its projecting sides forming the 55 base of the bed.

The side boards, 6, which are united at their ends, are divided and hinged together at a, so that the short or foot section shall fold over and upon the long or head section. A 60 bottom board, 8, is provided for the head-section, the under side of which, when the bed is in position for use, forms the ornamental front thereof when folded up. Attached to the inner face of the bottom board, 8, at each side 65 near the unobstructed edge thereof, I provide folding legs 9, adapted to project down and support the end of the head-section when the bed is extended, the other end being supported by the pivotal connection of the side boards 70 with the extended sides of the head of the bed.

The foot-section of the bed-bottom I usually leave without an under cover, only employing one or more transverse bars, 10, to brace and strengthen the same, while as a support therefor I provide the legs 11, pivoted to the inside of the side boards, 6, which in this section are of reduced width, the said legs being held in the same plane by means of a cross-bar, 12, uniting them, and are adapted to fold up when 75 not needed within said side boards.

A woven-wire spring, 13, attached in the ordinary manner to the bed-bottom at the foot, is carried forward to pass over a roller, 14, journaled in plates 15, attached to the inner 80 face of the side boards, 6, at the head, around and under the said roller 14 to a connection with a transverse suspended bar, 16. An eye-bolt, 17, is passed through this suspended bar 16 at each end, adapted to receive a link or bar, 90 18, connected to one end of a perforated connected plate, 19, the other end of the said plate being connected by a similar link or bar to a staple, 20, having a plate integral therewith, by which it is attached to the bottom board, 8, of 95 the head-section of the bed.

A metal rod, 21, threaded at both ends, is passed through the central perforation of the connecting-plates 19 and nuts 22, which may be provided with the usual wings, are screwed 100

from the outside upon the ends of the rod to bear against the outer face of the said connecting-plates 19, while similar nuts, 23, upon the rod 21 bear against said plates upon the 5 other or inner side.

The purpose of the bar 21, which I style a "take-up" bar, and the link-connections with the transverse suspended bar 16 and the bottom board, 8, is to take up the slack of the 10 woven-wire mattress and regulate the tension thereof.

When the mattress is first attached in the manner above described, the length is so regulated as that when the attachments are made 15 the connecting-plates 19 will be near the ends of the take up bar 21. As the mattress afterward sags or becomes loose from wear, the nuts 22 and 23 are turned so as to carry the connecting-plates 19 upon the said take-up bar 21 toward 20 the center thereof. The links 18 will then pull equally upon the suspended mattress-bar 16 and bottom board, 8, keeping the said bottom board, take-up bar, and mattress-bar parallel, thereby exerting an equal strain 25 or tension upon the entire surface of the woven wire. The farther the plates 19 are carried toward the center, the tighter the mattress is drawn. When carried toward the ends of the take-up bar, the looser it becomes.

30 It is not absolutely necessary to carry both plates toward the center to tighten the mattress. The manipulation of one plate is sufficient, as the rods or links will accommodate themselves to any irregularity and keep the 35 draft upon the mattress equalized.

Across the under side of the woven-wire mattress and attached thereto I fasten a light transverse stretcher-bar, 24, purposed to keep the said mattress from buckling as it is drawn 40 across the roller and from sagging at the edges.

The legs 9, which support the outer end of the head-section of the bed bottom, are constructed with a flat top plate, 25, at right angles to the length of said legs and integral therewith, and provided upon one edge thereof are 45 knuckles, adapted to register with similar knuckles formed in the vertical portion of the angular standards 26, attached to the inner face of the bottom board, 8, near the edge thereof.

50 A pivot-pin, 27, passing through the said registering-knuckles, completes the hinged connection of the said legs. The knuckles on the said top plates and standards are so spaced as that the legs 9 will have play about the 55 length of one knuckle toward the front of the head-section, to which they are attached. Another vertical standard, 28, having its top and bottom bent over at right angles thereto in opposite directions, is secured by means of its 60 lower horizontal portion to the bottom board, 8, upon the outside of the hinged legs 9, so that the top horizontal portion thereof will project over the top plate, 25, of the legs 9 when said legs support the head-section, to 65 form a stop or stay therefor, while a bent spring, 29, secured to the vertical portion of

the standards 28, tends to keep the legs in a vertical or supporting position. When the legs are not required as a support, they are carried up parallel with the top edge of the 70 bottom board, 8, and toward the head-board the distance above specified, to rest out of the way upon said bottom board, 8, inside the edge thereof.

The pivotal connection of the folding united 75 legs 11, supporting the lower or foot section, is made by attaching to the inner face of the reduced side boards, 6, near the end thereof, a plate, 30, carrying a post, 31, upon which, near its intersection with the said plate, is provided 80 a stop, 32, as illustrated in Fig. 6. A collar, 33, having a face-plate, 34, integral therewith, is passed through the legs 11 and secured thereto by the face-plate 34, bearing upon the outside thereof. The said collar, which is provided with a recess, 35, at the end, extending about one-quarter its circumference, thus secured, is now passed over the post 31, the recess 35 therein engaging the stop 32, formed on the said post. A bent spring-washer, 36, is 85 then slipped over the post to a bearing upon the collar-plate 34, and a nut, 37, is screwed upon the threaded portion of the post 31, the bearing of which upon the bent washer 36 regulates the tension of the said legs 11. It will 90 be seen from the above construction that the legs 11 can move but the quarter of a circle, or from a closed position within the side boards, 6, and parallel thereto, to an open or 95 vertical position at right angles to said side 100 boards, and vice versa.

The foot-board 38 is adapted to swing from a vertical position, when the bed is opened, to a position at an angle over and upon the mattress and clothes, to hold the same in position 105 when the sections are folded over to close the bed. This is accomplished by pivoting in any suitable manner curved arms 39 to the reduced side boards, 6, and attaching them to the outer edge of the foot-board 38 upon each side, as 110 shown.

In closing the bed, the foot-board is swung over upon the mattress, the legs of the foot-section folded up, and the said section folded over upon the head-section of the bed-bottom. 115 This loosens the mattress and permits the take-up bar and link-connections to rest upon the bottom board, 8. The legs 9 of the head-section are now carried up to their position upon and inside the edge of the said bottom board, 120 and the head-section, carrying the foot-section of the bed-bottom, is carried up by means of a spring (not shown) and slight outside aid from a horizontal to a vertical position inside the projecting sides of the head-board. The hinged top of the head-board is then let fall to its position as a cover for the hinged ends of the side boards of the bed. The mattress, take-up bar, and connections, when the bed is folded, assume the position shown in Fig. 3.

I am aware that it is not new to pass the end of a flexible mattress over a roller journaled in

the bed-bottom before carrying said end to a connection with a tension device; and I do not broadly claim such construction.

Having thus described my invention, what I claim as new, and desire to secure by Letters Patent, is—

1. The combination, with a flexible mattress attached at one end to a bed-bottom, adapted to pass over a roller provided in the other end thereof, and a transverse bar secured to said mattress, of apertured plates flexibly connected to said bar and the bed-bottom and a rod carrying nuts engaging said plates, substantially as shown and described, and for the purpose herein set forth.

2. The combination, with a bed-bottom having plate 15 attached to the side boards thereof and a wire mattress attached at one end thereto, adapted to pass over a roller, 14, journaled in said plates, and a transverse bar, 16, having eyebolts 17, of the apertured plates 19, attached

to said transverse bar 16, and the bottom board, 8, by rods 18, and the threaded take-up bar 21, adapted to carry nuts 22 and 23 upon each side of said apertured plates, substantially in the manner and for the purpose herein set forth.

3. The combination, with the head-section of a folding bed having attached to its bottom board, 8, vertical standards 28, provided with a spring attached thereto, and a horizontal top projection, of the hinged legs 9, provided with a top plate, 25, at right angles thereto, and a vertical standard, 26, secured to said bottom board, 8, the said horizontal projection of the standard 28 adapted to register over the top plate, 25, substantially as shown and described, for the purpose herein set forth.
